PARTY PICK FOR SANDWICHES AND HORS D'OEUVRES

Hyman J. Cohen, Arlington, Va.

Application September 14, 1955, Serial No. 37,923

Term of patent 3½ years

(Cl. D86—10)

Fig. 1.

Fig. 2.

Figure 1 is a view in front elevation of a party pick for sandwiches and hors d'oeuvres in accordance with my invention; and

I claim:

The ornamental design for a party pick for sandwiches and hors d'oeuvres, as shown.
